FOREIGN PATENT DOCUMENTS

CA 96914 S 10/2002

Primary Examiner — Lakiya Rogers*Assistant Examiner* — Harold E Blackwell, II(74) *Attorney, Agent, or Firm* — GE Global Patent Operation; Peter T. DiMauro(57) **CLAIM**

The ornamental design for a LED directional lamp with lens, as shown and described.

DESCRIPTION

FIG. 1 is a perspective view of a LED directional lamp with lens in accordance with the present design;

FIG. 2 is a side view of the LED directional lamp with lens shown in FIG. 1;

FIG. 3 is a top plan view of the LED directional lamp with lens shown in FIG. 1; and,

FIG. 4 is a bottom plan view of the LED directional lamp with lens shown in FIG. 1.

The broken lines illustrate portions of the LED directional lamp with lens which form no part of the claimed design. Any shading forms no part of the claimed design and is provided to illustrate contour only and is not an indication of texture, gloss, and the like.

1 Claim, 4 Drawing Sheets(56)
